UNITED STATES PATENT OFFICE.

RALPH R. BOSTIC, OF LOS ANGELES, CALIFORNIA.

SNAP-ON SUCKER-ROD GUIDE.

Application filed May 1, 1926. Serial No. 105,996.

This invention relates to snap-on sucker rod guides.

The general object of the invention is to provide a sucker rod guide which can be 5 economically manufactured and quickly installed.

A specific object of the invention is to provide a flexible member for snapping on a sucker rod to act as a guide therefor.

10 Another object of the invention is to provide a sucker rod guide comprising a piece of metal or other flexible material which is arranged in spiral form and is also adapted to be placed upon a sucker rod.

15 A further object of the invention is to provide a spirally wound sucker rod guide having means thereon for engaging the sucker rod.

Other objects of the invention will be apparent from the following description taken 20 in connection with the accompanying drawings wherein:

Fig. 1 is a central sectional view showing a portion of a well with a pump casing therein 25 having a sucker rod equipped with my invention.

Fig. 2 is a view similar to Fig. 1 on a larger scale.

Fig. 3 is a section on line 3—3 of Fig. 2. 30 Fig. 4 is an elevation showing the manner in which the guide is arranged about a sucker rod.

Fig. 5 is a sectional view of the modified form of my invention, and

35 Fig. 6 is a sectional view showing a further modification of my invention.

Referring to the drawing by reference characters I have shown a well casing at 10. Within this well casing I show a pump casing 40 at 11. A sucker rod is shown at 12.

The sucker rod guides embodying the features of my invention is shown at 14. This guide is preferably flexible and may be made of metal or other material. My guide is 45 constructed to normally take the position of a spiral, and the upper and lower ends of the spiral if desired may be bent abruptly inwardly as at 15, with the extreme ends 16 pitched toward the center of the spiral so 50 that the edge 17 may bite into the rod 12 to prevent up and down movement of the rod between the rod and guide.

55 The guide being spirally arranged does not prevent the flow of fluid through the pump casing, but does effectively support the sucker rod. The guide will also provide an

outer edge which as the rod moves up and down in the well prevents the accumulation of paraffine or other solids on the inner wall of the casing. The guide will be of material which is of sufficient softness to cause no injury to the inside of the casing 11 due to the rubbing contact. The guide may be provided with perforations 18 which may be distributed at intervals as desired. 60 65

The inner diameter of the guide is preferably slightly less than the outer diameter of the sucker rod so that the resilient properties of the guide will maintain it in proper position. The guide will be sprung as 70 shown in Fig. 4 when installing it.

In Fig. 5 the guide is shown as provided with supports 20 for rollers 21, which are adapted to engage the inner wall of the casing 11. These rollers may be used whenever 75 desired.

In Fig. 6 I show a modification of my invention wherein the flexible sucker rod guide 25 comprises a flexible strip of material such as compressed fibre or other substances in 80 which a flexible strip 26 of metal or other material is imbedded. The flexible strip 26 serves to maintain the shape of the guide while the softer material 25 prevents wear but does not prevent the flow of fluid through 85 the casing 11.

From the foregoing description it will be apparent that I have provided an economical and effective sucker rod guide which can be quickly installed. My invention also serves 90 as a casing or tubing protector since it properly centers the sucker rod so that the latter remains out of contact with the inner wall of the casing or tubing.

Having thus described my invention what 95 I claim is:

1. In combination with a well casing, a sucker rod movable in said casing and means engaging said casing and said sucker rod to prevent flexing of said rod, said means comprising a strip of material arranged to entirely surround and to engage said rod throughout substantially its entire length. 100

2. In combination with a well casing having a sucker rod movable therein, a member arranged on said sucker rod and engaging said casing, said member comprising a flat strip of material rectangular in cross section and bent so that one continuous edge of said strip engages said rod while the 105 opposite edge of the strip rod engages said casing. 110

3. In combination with a sucker rod, a guide comprising a strip of material shaped to surround and engage the sucker rod throughout its entire length, said guide forming a curved channel in conjunction with the rod. 25
4. In combination with a sucker rod, a flexible guide comprising a strip of material bent to spiral form and having portions thereof gripping said sucker rod, the extremity of said strip having an edge bent substantially parallel to the rod to engage the rod. 30
5. A sucker rod guide comprising a strip of material bent to form a spiral, the ends of said spiral being bent abruptly inwardly and having the extreme end pitched at a slight angle to the spiral whereby a sharp edge is provided for engaging a sucker rod. 35
6. A sucker rod guide comprising a strip of material arranged in curved form and having a central aperture adapted to receive a sucker rod, said spiral having a normal 40

central diameter slightly less than the diameter of the sucker rod which it is adapted to engage, whereby there will be tight frictional engagement between the guide and rod.

7. In combination with a well casing, a sucker rod movable in said casing and guide means engaging said casing and said sucker rod, said guide means engaging the periphery of the rod and having a spirally arranged wall therein. 35

8. In combination with a well casing having a sucker rod movable therein, a member arranged on said sucker rod and engaging said casing, said member comprising a strip of flat flexible material rectangular in cross section, said strip being bent so that one narrow edge of the strip engages said casing while the other narrow edge engages said rod to hold the strip in position. 40

In testimony whereof, I hereunto affix my signature.

RALPH R. BOSTIC.
